BRACKET FOR ARMCHAIR ACCESSORY SEATS

Filed May 31, 1944

UNITED STATES PATENT OFFICE

2,453,007

BRACKET FOR ARMCHAIR ACCESSORY SEATS

William O. Flatt, Fort Worth, Tex.

Application May 31, 1944, Serial No. 538,167

3 Claims. (Cl. 248—300)

1

This invention relates to an accessory for use in conjunction with arm chairs of the type customarily found in barbers' establishments, dentists' offices, etc., and has particular reference to a simplified means whereby an elevated seating surface, particularly useful in handling children, may be readily and quickly associated with the chair by resting the same upon the arms thereof in such manner that it will remain substantially immobile when in use.

An important object of the invention is to simplify the difficulties encountered in handling children in chairs of the type described above by means of a simple, inexpensive arrangement of relatively few parts and to do so in such manner that the elements which form the combination may be separately obtained and easily assembled by one unskilled in mechanics of this sort.

A further object of the invention is to provide a simple stabilizing element which may be used in conjunction with a conveniently available seating surface, such as a board, and associated therewith easily and quickly in such position as to accomplish the desired end of stabilizing the seat in elevated position and prevent it from shifting laterally or transversely when occupied.

Still another object is to simplify the design of the stabilizing element to be associated with the seating surface to such an extent that blanks for the manufacture thereof may be cheaply produced and the forming operation reduced to a minimum of sequential steps.

Various other objects and meritorious features of the invention will become apparent from the following description taken in conjunction with the drawings, wherein like numerals refer to like parts throughout the several figures, and wherein:

Figure 1 is a perspective illustrating my improved device in operative position upon a conventional barber's chair;

Fig. 2 is a top plan view illustrating the stabilizing arrangement;

Fig. 3 is a rear elevation of the assembly;

Fig. 4 is an intermediate section through the accessory seat;

Fig. 5 is a perspective illustrating the blank from which my stabilizing bracket is formed;

Fig. 6 is a similar view illustrating an initial step in forming the bracket, and

Fig. 7 is a similar view illustrating the completed stabilizing bracket.

The invention for purposes of illustration has been reduced to its bare essentials and for pur-

2

poses of convenience it may often be desirable to use for the accessory or elevated seat a simple board 10 of such length as to rest securely upon the arms 12 and 14 of an arm chair such as those customarily used by barbers, dentists, etc. To each end and on the rear as viewed in Fig. 1 is secured one of my stabilizing brackets. Each bracket comprises a main guide wing 16 and a secondary guide wing 18 having a margin in common with wing 16, together with a supporting wing 20 which lies in a plane normal to that of both wings 16 and 18 and extends outwardly from the included angle lying between said wings.

In Fig. 5 I have illustrated a preferred form of blank from which a stabilizing bracket such as that just described may be readily formed. The bracket blank consists of a rectilinear element, preferably of metal which may be formed in a stamping machine. In some instances it may be preferable to use very thin metal which can be expeditiously formed by hand in a manner to be described hereinafter, thereby permitting distribution of the blanks as such and reducing the cost of manufacture inasmuch as the stabilizing element may be formed in such cases from the blank by the user himself. The blank is provided intermediate its length with a transverse die cut 22 which preferably extends approximately half the width of the blank. A line 24 extended from the end of die cut 22 may be weakened as indicated by the numeral 24 to facilitate bending about the line. One of the wing portions so formed may be provided with a weakened line 26 extending longitudinally from the base of the die cut 22 across the face of one wing. Openings for the reception of securing means, as indicated at 28, may be provided in the upper portion of each of the wings formed by the combined die cut line 22 and weakened line 24. As shown, these openings are in longitudinal alignment with die cut 22.

The blank may then be bent or formed to right-angle shape as illustrated in Fig. 6, the weakened line 24 facilitating this operation. The final step is to bend or form the upper portion of that wing across which weakened line 26 extends longitudinally to thereby fashion supporting wing 20.

Where the use of a simplified seating surface such as a board or the like is contemplated, and one of the important features of the invention resides in the fact that such a surface may be used expeditiously for the intended purpose, it is preferable that the supporting wing 20 be formed or bent along a line so positioned with reference to

the main guide wing 16 that the upwardly projecting portion thereof, indicated at *x* in Fig. 7, will approximate at least the width of the board 10. The openings 28 are so positioned in wing 16 that screws or other suitable fastening means inserted therethrough will solidly engage the edge of the seating surface. As will be seen, the seat engaging faces of the bracket lie flush against the surfaces of the seat when the brackets are positioned.

It is also important that the secondary guide wing 18 and the lower portion of main guide wing 16 extend downwardly below the plane of supporting wing 20 a sufficient distance to form a solid abutment against the inner face and rear face of arms 12 and 14, respectively, thereby positively precluding lateral or forward shifting of the seat.

In the form illustrated wherein a simple board is used to provide the seating surface 10, the rear face of main guide wing 16 abuts the forward face of chair back 11 as well as the rear faces of arms 12 and 14, thereby precluding rearward shifting movement of the seat as well as forward shifting movement thereof.

While with some constructions it might be advisable to use other types of securing means, screws 28 have been used in the simplified arrangement disclosed herein for purposes of illustration to fasten the stabilizing brackets to the seating surface.

Having described a specific form of the invention, various modifications thereof will be apparent to those skilled in the art and for that reason I wish to limit myself only within the scope of the appended claims.

What I claim is:

1. A stabilizing bracket adapted for use with a flat seat element in the manner described comprising a main guide wing, a secondary guide wing extending at right angles thereto and having a margin in common with a portion only of a margin of the main guide wing to thereby leave a projecting portion of the main wing, and a supporting wing extending away from the secondary wing in a plane normal to those in which the main and secondary guide wings lie, said supporting wing lying outside the angle included between said guide wings and being spaced from the margin of the projecting portion of the main wing a dis-

tance approximately the width of the seat element.

2. A stabilizing bracket adapted for use with a flat seat element in the manner described comprising a main guide wing, a secondary guide wing extending at right angles thereto and having a margin in common with a portion only of a margin of the main guide wing to thereby leave a projecting portion of the main wing, and a supporting wing extending away from the secondary wing in a plane normal to those in which the main and secondary guide wings lie, said supporting wing lying outside the angle included between said guide wings and having a fastener opening in the main guide wing positioned above its line of joiner with the secondary guide wing, and a fastener opening in the supporting wing and being spaced from the margin of the projecting portion of the main wing a distance approximating the width of the seat element.

3. A bracket formed from an integral rectangular blank and comprising a main guide wing formed by one end portion of the blank, and two wings formed from the other end of the blank, said wings constituting a secondary guide wing extending at right angles to the main wing and having a margin in common with a portion only of a margin of the main guide wing, and a supporting wing extending away from the secondary wing in a plane normal to those in which the main and secondary wings lie, said supporting wing lying outside the angle included between said guide wings.
